Conrad P. Heusler
ATTORNEY.

UNITED STATES PATENT OFFICE.

DANIEL G. CAREY, OF ELMIRA, NEW YORK.

VAGINAL SUPPORT.

1,230,112.

Specification of Letters Patent. Patented June 19, 1917.

Application filed January 14, 1916. Serial No. 72,126.

To all whom it may concern:

Be it known that I, DANIEL G. CAREY, a citizen of the United States, and resident of Elmira, in the county of Chemung, in the State of New York, have invented new and useful Improvements in Vaginal Supports, of which the following, taken in connection with the accompanying drawings, is a full, clear, and exact description.

10 This invention relates to certain improvements in uterus supports commonly known as "pessaries" for preventing prolapse of the uterus.

The main object is to reduce to a minimum 15 the liability of excessive irritation of the organs to which this class of instruments is applied, and at the same time to render such devices self retaining without inconvenience to the user or liability of displacement 20 when in use.

Another object is to provide the retaining ring or bulb with a separable core and stem capable of being easily and quickly taken 25 apart for cleansing and sterilizing when necessary without in any way affecting the integrity or form of the flexible ring.

Other objects and uses will be brought out 30 in the following description.

In the drawings—

35 Fig. 1 is a top plan of a pessary embodying the various features of my invention,

Fig. 2 is a side elevation of the same,

Fig. 3 is a longitudinal section of the same 35 device,

Fig. 4 is a sectional view similar to Fig. 3 showing a divided core.

40 Figs. 5 and 6 are perspective views of the cores shown in Figs. 3 and 4.

45 The pessary shown in Figs. 1, 2 and 3 comprises a hollow flexible ring —1— and a core —2— having a separable stem —3—, the ring —1— being circular in plan and also in cross section and is preferably made 50 of soft rubber inflated with air to an extent sufficient to retain its circular form without losing its pliability.

The core —2— preferably consists of a 55 rigid tubular sleeve of light non-corrodible material such as aluminium, hard rubber or its equivalent of less length than the axial depth of the ring —1— and is provided with enlarged end heads —4— and —5— and a reduced connecting neck —6— for 60 receiving and frictionally retaining the ring thereon.

For this purpose the external diameter of the neck —6— is slightly greater than the normal inner diameter of the central opening in the ring and its sides are concaved 60 lengthwise to conform approximately to the adjacent convex walls of said ring while the diameters of the end heads —4— and —5— are somewhat greater than the central opening in the ring and fit snugly against the 65 adjacent walls thereof to hold the core and ring against relative endwise displacement under ordinary use in removing or replacing the device from or into the vagina but allowing said parts to be separated when 70 necessary for cleansing or sterilizing by applying sufficient force to the ring to spring it over one or the other of the heads.

The outer head —5— is preferably of 75 slightly greater diameter than the inner head to afford greater resistance to the outward displacement of the ring relatively to the core when placing the pessary in operative position while the relatively smaller inner head allows the pneumatic ring —1— 80 to be expanded thereover and upon the reduced neck of the core but is of sufficiently larger diameter than that of the opening through the ring to hold said ring against accidental displacement from the core when 85 removing the pessary from the vagina by the stem.

This stem is made of rigid non-corrodible material, such as aluminium or its equivalent, of sufficient length to enter the mouth 90 of the vagina when the pessary is adjusted for use for balancing and holding the ring —1— in its most effective position, said stem having a reduced threaded end —7— screwed into a central threaded opening 95 —8— in the core —2— to permit it to be removed if necessary for cleansing or sterilizing the various parts or for any other purpose.

The opposite end of the stem is enlarged 100 forming a head —9— for additionally balancing and supporting the ring in the vagina and is provided with branch passages —10— leading from its periphery to a main central passage —11— which extends entirely through the stem from end to end so as to communicate with the interior of the uterus to facilitate excretions therefrom.

The ring —1— and its core —2— constitute 110 the head of the pessary and by making the ring circular in cross-section and using a core of less length than the vertical depth

of the ring leaves the central portions of opposite sides of the head more or less concave which enables the pessary to fit more closely against the walls of the vagina and affords 5 greater resistance to the involuntary withdrawal or expulsion of the pessary by reason of the fact that the lower face of the head is more abrupt and avoids the outward wedging action incidental to the use of 10 pessaries with inverted conical heads.

In Figs. 4 and 6 is shown a slightly modified form of core —2'— divided diametrically through the reduced portion or neck to form opposite clamping sections —11'— 15 and —12—, the upper section —11'— being provided with a threaded aperture for receiving the threaded end of the stem while the lower section is provided with a slightly larger smooth bore through which the 20 threaded end of the stem may pass freely, thus permitting the two sections to be applied to opposite faces of the ring —1— without expanding the latter whereupon said sections may be drawn together by the 25 screw-stem to firmly clamp the ring to the core.

The threaded portion of the stem —3— is rather long which permits the device to be extended in length when placing it in operative position, after which the stem may be screwed up as far as possible to avoid external projection and consequent inconvenience to the user, particularly in a sitting 30 posture.

35 What I claim is:

1. A vaginal support comprising a sealed pneumatic ring, a core fitted in the center of the ring and curved coincident thereto, the transverse axis of the core being disposed 40 below the transverse axis of the ring with

the upper and lower edges thereof terminating within the upper and lower edges of the ring, and a balancing stem projecting axially from the center of the core.

2. A vaginal support comprising a sealed 45 hollow flexible ring inflated with air, a core fitted centrally in said ring and curved coincident thereto, the transverse axis of the core being disposed below the transverse axis of the ring with the upper and lower edges 50 thereof terminating within the upper and lower edges of the ring, and a hollow balancing stem projecting axially from the center of the core.

3. A vaginal support comprising a flexible 55 ring, a rigid core fitted centrally in the ring and curved coincident thereto, the transverse axis of the core being disposed below the transverse axis of the ring with the upper and lower edges thereof terminating 60 within the upper and lower edges of the ring, and a rigid stem secured to and projecting axially from the center of the core.

4. A vaginal support comprising a flexible 65 ring, a rigid core fitted centrally in the ring and curved coincident thereto, the transverse axis of the core being disposed below the transverse axis of the ring with the upper and lower edges thereof terminating 70 within the upper and lower edges of the ring, and a rigid stem having screw connection with the core and projecting axially therefrom.

In witness whereof I have hereunto set my hand this 23rd day of September 1914. 75

DANIEL G. CAREY.
